WRAPPING FOR CONFECTIONARY

Daniel Pearson, Culver City, Calif., assignor to W. R.
Grace & Co., New York, N.Y.

Continuation of abandoned design application Ser. No.
166,328, July 26, 1971. This application Nov. 21, 1972,
Ser. No. 308,609

Term of patent 14 years

Int. Cl. D9—05

U.S. Cl. D9—250

FIG. 1

FIG. 2

FIG. 1 is a top plan view of the wrapping for a confectionary showing my new design; and

FIG. 2 is a side elevational view thereof.

This application is a continuation of application Ser. No. D. 166,328 filed July 26, 1971, now abandoned.

I claim:

The ornamental design for a wrapping for a confectionary, as shown and described.
